DESIGN FOR AN OIL BURNER CASING

William J. Smith, Rocky River, Ohio

Application June 29, 1934, Serial No. 52,390

Term of patent 14 years

To all whom it may concern:

Be it known that I, WILLIAM J. SMITH, a citizen of the United States, residing at Rocky River, in the county of Cuyahoga, and State of Ohio, have invented a new, original, and ornamental Design for an Oil Burner Casing, of which the following is a specification, reference being had to the accompanying drawing forming a part thereof.

In the drawing, Figure 1 shows a perspective

view of an oil burner casing embodying my design looking toward one end thereof and Figure 2 shows a perspective view of the oil burner casing looking toward the opposite end thereof.

I claim:

The ornamental design for an oil burner casing, substantially as shown and described.

WILLIAM J. SMITH.
